AUXILIARY TOILET SEAT

Esther B. Potts and Frances D. La Roche, Waco,
Tex.; said Frances D. La Roche now by change
of name Frances D. Allen

Application December 7, 1945, Serial No. 633,313

1 Claim. (Cl. 4—239)

1 This invention relates to toilet seats and more particularly to a portable auxiliary toilet seat which may be set in place upon the usual toilet seat to accommodate a small child.

Auxiliary toilet seats for babies and small children are now in use but they have been found unsatisfactory because they are cumbersome and heavy and cannot be conveniently carried from one place to another when traveling and also are in the way when not in use due to the fact that they cannot be compactly folded for storage.

Therefore, an important object of the present invention is to provide a toilet seat of the character specified which is so formed that it is firmly held in set-up position and at the same time may be flatly and compactly folded after being used and put away in a small space until again needed.

Another object of the invention is to provide a portable auxiliary toilet seat formed of corrugated cardboard or the like which is of light weight and may be conveniently packed in a traveling bag without adding appreciably to the weight thereof.

A further object is to provide an auxiliary toilet seat which is formed from a single blank of sheet material so scored or creased that it may be easily and quickly set up for use with portions of the blank forming the sides and the back of the seat interengaged to hold them upright.

A still further object of the invention is to provide an auxiliary seat which is held in place upon the usual toilet seat by a flexible attaching element associated with the back of the auxiliary seat and having end portions extending from opposite sides thereof so that they may be tied about a portion of the usual seat, the flexible attaching element being removed from the back when the auxiliary seat is to be folded and used to secure the auxiliary seat in a folded condition.

An additional object is to provide an auxiliary toilet seat having a flap across its front end which is adapted to extend downwardly over the front portion of the usual toilet seat and bowl to serve as a shield.

In the accompanying drawings:

Figure 1 is a perspective view of the improved auxiliary toilet seat in set-up position.

Figure 2 is a longitudinal sectional view through the toilet seat and showing the same in place upon the usual toilet seat and associated bowl which are indicated by dotted lines.

Figure 3 is a horizontal sectional view through 55 side walls are held in an upright operative posi-

2 the auxiliary toilet seat taken along the line 3—3 of Figure 2.

Figure 4 is a transverse sectional view taken along the line 4—4 of Figure 2.

Figure 5 is a top plan view showing the auxiliary seat as it appears folded when not in use.

Figure 6 is a sectional view taken along the line 6—6 of Figure 5.

Figure 7 is a view looking at the bottom of the folded auxiliary seat.

Figure 8 is a sectional view taken along the line 8—8 of Figure 5.

Figure 9 is a view of the blank from which the auxiliary toilet seat is formed.

15 The improved auxiliary toilet seat is formed from a single blank of corrugated cardboard or other suitable sheet material as shown in Figure 9 of the drawings. By reference to Figure 9 it will be seen that the blank has a body or seat portion 1 formed with an opening 2 of smaller size than the opening in the permanent or standard toilet seat upon which the auxiliary seat is to be positioned for use. The portion 1 is of such dimensions that it will rest flatly upon the seat 3 of the toilet bowl 4 with its opening 2 disposed over the opening of the seat 3.

20 The forward portion 5 of the blank is scored or creased transversely along the dotted line 6 so that it may be easily moved to an operative position at substantially right angles to the body portion 1 as shown in Figures 1, 2 and 4, or to an in-

25 operative position flatly against the under side of the body portion 1 as shown in Figures 5, 6 and 7. When the forward portion or flap occupies the operative position illustrated in Figures 1, 2 and 4, it serves as a shield to prevent contact of the person and clothing of the user with the front of the seat 3 and the bowl 4.

30 The blank is longitudinally scored or creased along the opposite side edges of the body portion 1 as indicated at 8, 8 to provide side portions 7 movable to upright positions to form side walls or guards for the auxiliary seat. The rear end portions 9 of the side walls 7 are severed from the rear portion 10 of the blank and scored trans-

35 versely along the dotted lines 11, 11 to provide flaps, which are adapted to be swung inwardly toward each other from opposite sides of the seat when the side walls are moved to the upright position of Figures 1, 2 and 4. The rear portion 45 10 is then folded upwardly along the line of scoring 12 and its free end portion 13 folded forwardly and downwardly along the line of scoring 14 into confining relation to the flaps 9 whereby the

50 rear portion 10 is held in an upright operative position of Figures 1, 2 and 4. The rear portion 10 is then folded upwardly along the line of scoring 12 and its free end portion 13 folded forwardly and downwardly along the line of scoring 14 into confining relation to the flaps 9 whereby the 55 side walls are held in an upright operative posi-

tion. The portion 13 fits snugly between the side walls 7 and has sufficient binding engagement therewith to frictionally hold it in securing relation to the flaps 9.

Before the rear portions 10 and 13 are moved into engagement with the flaps 9, a tape or cord 15 is placed across the seat in back of the flaps 9 with its end portions projecting beyond opposite sides of the seat to afford means for securing the auxiliary seat in place upon the main seat 3. The ends of the tape may be tied about the hinged portion of the main seat 3 or any other convenient part of the standard toilet.

A finger receiving notch 16 is cut in the free or lower edge of the portion 13 to facilitate its upward swinging and dislodgment from a position in front of the flaps 9.

As will be apparent, the improved auxiliary seat may be quickly folded and reduced to a flat compact mass and placed in a traveling bag or in a bath room cabinet where it will occupy a small space and be out of way. The tape 15 is tied about the folded seat to hold it in that condition.

Since the seat is formed of cardboard it is inexpensive and hence may be discarded in the event it becomes soiled.

Having thus described the invention, what is claimed is:

An auxiliary toilet seat formed from a single blank of foldable sheet material and having a seat

portion provided with an opening, side walls extending upwardly along opposite side edges of the seat portion and provided with inwardly projecting flaps extending toward each other at the rear end of the seat portion, and a rear portion extending upwardly from the seat portion and folded forwardly and downwardly over the flaps in straddling relation thereto to hold the side walls upright, the forwardly and downwardly folded part of said rear portion fitting snugly between and frictionally engaging the inner faces of the side walls to maintain the rear portion in operative relation to the flaps, the free edge of said rear portion being provided with a finger receiving notch.
